(57) **CLAIM**

The ornamental design for a canvas frame, as shown and described.

DESCRIPTION

FIG. 1 is a perspective view of the canvas frame.

FIG. 2 is a front view of the canvas frame.

FIG. 3 is a back view of the canvas frame.

FIG. 4 is a left side view of the canvas frame.

FIG. 5 is a right side view of the canvas frame.

FIG. 6 is a top view of the canvas frame.

FIG. 7 is a bottom view of the canvas frame; and, FIG. 8 is a magnified front view of the portion within box 8 of FIG. 2.

The cross-hatching shading in the figures is fragmentarily shown for convenience of illustration, it being understood that the cross-hatching is uniformly continued over the surface on which it appears.

The broken lines of FIGS. 1-8 are included for the purpose of illustrating environmental structure and form no part of the claimed design. The dash-dot broken lines in the figures are demarcating enlarged areas and form no part of the claimed design.
